CARD GAME BOARD

Miguel Lisboa, New York, N. Y.

Application March 29, 1948, Serial No. 145,409

Term of patent 14 years

(Cl. D34—5)

To all whom it may concern:

Be it known that I, Miguel Lisboa, a citizen of the United States, residing at New York, in the county of New York and State of New York, have invented a new, original, and ornamental Design for a Card Game Board, of which the following is a specification, reference being had to the accompanying drawing, forming a part thereof.

In the drawing:

Fig. 1 is a top plan view of a card game board, showing my new design; and

Fig. 2 is an elevational view of the same.

I claim:

The ornamental design for a card game board, as shown.

MIGUEL LISBOA.
